SAND BLASTING STENCIL

Carl E. Frick, Chicago, Ill., assignor, by mesne assignments, to Van Cleef Bros., Chicago, Ill., a partnership consisting of Noah Van Cleef, Felix Van Cleef, and Paul Van Cleef

Application October 28, 1937, Serial No. 171,452

8 Claims. (CL. 41—39)

The present invention relates generally to stencils for use in cutting letters, symbols, or designs on monument-forming stones or stonework by way of sand blasting. More particularly the invention relates to that type of stencil which comprises a sheet of sand resistant material and a coating of adhesive on the back face of the sheet, is adapted after application to the surface to be cut to have the desired letters, symbols or designs marked or penciled on the front face thereof and then cut out or removed by a knife or like sharp instrument, and serves in connection with the cutting operation, that is, when sand is blasted thereagainst in connection with cutting of the surface, to control the sand so that it encounters only the portions of the surface behind the cut outs and hence cuts by its abrasive action the desired letters, symbols or designs in the surface.

One object of the present invention is to provide a stencil of this type which is more efficient and practical than previously designed stencils of the same general character and also due to the character or composition of the sand resistant sheet is adapted to make sharper or better defined letters and has materially greater wearing or lasting properties.

Another object of the invention is to provide a stencil of the type under consideration in which the sand resistant sheet is formed or composed of vulcanized rubber and an admixture of glue to the end that the sheet as a whole is not too elastic and not only can be cut readily in connection with the formation of the desired letters, symbols or designs therein, but also possesses the necessary or proper amount of durability to withstand heavy sand blasting.

Another object of the invention is to provide a stencil of the type and character under consideration in which the coating on the back face of the sheet of sand resistant material is in the form of a rubber base pressure sensitive adhesive and not only permits the sheet to be applied readily to the surface to be cut but in addition forms a cushion or resilient backing for absorbing a portion of the shock or impact of the sand against the sheet.

A further object of the invention is to provide a sand blasting stencil which is generally of new and improved design and may be manufactured at a low and reasonable cost and in addition has or embodies a holland sheet for protecting the pressure sensitive rubber base adhesive coating on the back of the sand resistant sheet prior to application of the sheet to the work, that is, the surface to be cut.

Other objects of the invention and the various advantages and characteristics of the present stencil will be apparent from a consideration of the following detailed description.

The invention consists in the several novel fea-

tures which are hereinafter set forth and are more particularly defined by claims at the conclusion hereof.

In the drawing which accompanies and forms a part of this specification or disclosure and in which like numerals of reference denote corresponding parts throughout the several views:

Figure 1 is a perspective of a monument-forming stone having applied to the front face thereof of a stencil embodying the invention;

Figure 2 is a perspective showing the stencil before stripping or peeling of the holland sheet from the coating of pressure sensitive rubber base adhesive in connection with application of the sand resistant sheet to the work;

Figure 3 is a fragmentary perspective of the holland sheet over which the sheet forming material is calendered or spread in connection with fabrication of the stencil;

Figure 4 is a fragmentary perspective showing the holland sheet of Figure 3 with the sheet forming material calendered or spread thereover;

Figure 5 is a fragmentary perspective showing the holland sheet and sand resisting sheet after the vulcanizing operation and with the coating of pressure sensitive rubber base adhesive on the exposed face, that is, the back face of a sand resistant sheet;

Figure 6 is a fragmentary perspective view showing the original holland sheet, the sand resistant sheet, and the coating of pressure sensitive rubber base adhesive after application of the second holland sheet to the adhesive coating;

Figure 7 is a fragmentary perspective showing the sand resistant sheet after removal of the original sheet of holland; and

Figure 8 is a fragmentary perspective showing the complete stencil.

The stencil which is shown in the drawing constitutes the preferred embodiment of the invention. It is shown or illustrated in connection with a monument-forming stone S and serves, as hereinafter described to control a sand blast in connection with the cutting or formation of letters, symbols, or designs on the stone. As shown in Figure 8, the stencil embodies as the principle parts or elements thereof a sheet 9, a coating 10 on the back face of the sheet 9, and a protective sheet 11 of holland for the coating 10. The coating 10, as hereinafter described, is formed of pressure sensitive rubber base adhesive and is adapted, after removal of the holland sheet 11 to secure the sheet 9 in place on the stone S. The sheet 9 is formed of sand resistant material and is adapted when the stencil is in place on the stone to have the desired letters, symbols, or designs penciled thereon and then cut out or removed from it by a knife or similar sharp

instrument. When a sand blast is directed against the stencil during use of the latter, the sheet 9 serves to control the sand so that it encounters only the portions of the surface of the stone behind the cut outs and hence cuts by its abrasive action the desired letters, symbols or designs in the stone.

The sheet 9 is formed or composed of vulcanized rubber and an admixture of glue. It is 10 preferably made of the following ingredients in substantially the proportions or amounts specified:

	Ingredients	Pounds	Ounces
15	Smoked rubber sheets (hard tough plantation type rubber)	50	0
	Whiting	98	0
	Zinc oxide	3	0
	Pearl glue	50	0
20	Petrolatum	0	4
	Accelerator (tetramethyl-thiuram disulphide)	0	6
	Sulfur	0	10

In connection with fabrication of the stencil the aforementioned ingredients are properly milled and mixed together and then while in the form of a plastic mass are calendered or otherwise spread over a sheet 12 of holland. Preferably the mass is spread over the sheet 12 until it has a thickness of approximately .045 inch. The whiting content of the sheet forming material acts as a stiffener and a filler and the petrolatum serves as a dispersing or softening agent and to make the mass more workable. The sulfur constitutes the vulcanizing agent for the rubber and the tetramethyl-thiuram disulphide operates as an accelerator for the vulcanizing agent. The zinc oxide content of the material serves to activate the accelerator, that is, the tetramethyl-thiuram disulphide, and the pearl glue operates to toughen the mass or material as a whole and also to harden or reduce the elasticity of the rubber. After the calendering or spreading operation the holland sheet 12 with the layer of sheet forming material thereon is placed in an oven or like heating apparatus for a period of 18 hours and subjected to a temperature of approximately 200° F. This serves to vulcanize the rubber content of the material and results in formation of the sheet 9. Due to the fact that the latter is composed of vulcanized rubber and an admixture of glue it is not only extremely tough and durable but also sand resistant and substantially inelastic.

The adhesive coating 10 is applied to the exposed face of the sand resistant sheet 9 by way of a calendering or spreading operation after the vulcanizing step. It is essentially permanently tacky and preferably is formed of the following ingredients in substantially the proportions specified:

	Ingredients	Pounds	Ounces
	Milled white crepe rubber	38	0
65	Zinc oxide	12	0
	Burgundy pitch	16	12
	Oregon balsam	1	8

The Burgundy pitch content of the adhesive serves as a softener and makes the adhesive extremely tacky. The Oregon balsam due to the fact that it is non-volatile makes the adhesive permanently tacky. After application of the adhesive coating 10 to the sand resistant sheet 9 the sheet 11 of holland is applied to the exposed face of the coating. This sheet 11 corre-

sponds in size to the coating 10 and serves to prevent the latter from adhering to objects prior to use of the stencil. During or after application of the holland sheet 11 to the pressure sensitive rubber base adhesive 10 the holland sheet 12 is removed from the front face of the sand resistant sheet 9. Upon removal of the sheet 12 a fine layer 13 of talc is applied to the exposed or front face of the sheet 9 by way of dusting. The talc layer 13 prevents the sheet 9 from having any adhesive tendencies and permits the stencil to be rolled without any likelihood of the exposed or front face of the sheet 9 adhering to the exposed face of the holland sheet 11. In addition it forms a smooth surface or facing on which the letters or symbols to be cut may be readily marked. The holland sheet 12 on which the sand resistant sheet 9 is formed serves as a backing for the sheet forming material and also to permit the material to be readily handled at the conclusion of the vulcanizing operation. By reason of the fact that the coating 10 is in the form of a permanently tacky pressure sensitive rubber base adhesive the stencil may be readily applied to the work, that is, the surface to be cut, without a preliminary wetting or moistening operation and also permits the stencil to be readily removed after the sand blasting step. In addition it serves as a cushion type backing for the sand resistant sheet 9 and by absorbing the shock or impact of the sand as it impinges against the sheet 9 increases materially the lasting properties of the sheet. Another feature or advantage of employing a coating of pressure sensitive adhesive resides in the fact that the sheet 9 is firmly held in place against the work during the sand blasting operation.

In using the stencil in connection with sand blasting to form letters on the stone S the holland sheet 11 is first stripped or peeled from the coating 10 of pressure sensitive rubber base adhesive. Thereafter the stencil is pressed against the surface to be cut or lettered in order to bring the coating 10 into adhesively connected relation with the latter. Thereafter the letters to be cut in the stone S are penciled or otherwise marked on the talced front face of the sheet 9 and are cut out or removed by a sharp knife or like tool. At the conclusion of this operation or step sand is blasted against the sheet 9. During the sand blasting operation the sheet controls the sand so that it encounters only the portions of the surface of the stone S behind the cut outs and hence cuts by its abrasive action the desired letters in the surface. By reason of the fact that the sheet 9 is formed of a composition of vulcanized rubber and glue it resists any abrasive or wearing effect of the sand and hence the portions thereof which remain after the letter cutting operation protect the contiguous portions of the surface of the stone from abrasion by the sand. After the sand blasting operation the stencil is stripped or peeled from the cut surface.

The herein described stencil due to the material of which the sand resistant sheet 9 is formed is characterized by the fact that it is exceptionally durable and long lasting. In addition it is characterized by the fact that it is adapted to make extremely sharply defined letters and may be quickly and readily placed in its operative position. In view of the simplicity of its method of manufacture the stencil may be produced at a low and reasonable cost.

The invention is not to be understood as restricted to the details set forth, since these may

be modified within the scope of the appended claims, without departing from the spirit and scope of the invention.

Having thus described the invention, what I claim as new and desire to secure by Letters Patent is:

1. As a new article of manufacture, a stencil designed for use in cutting letters, symbols or designs on a surface by way of sand blasting and comprising a sand resistant sheet adapted to be placed against the surface and upon proper shaping thereof to control the sand blast so that it forms or cuts the desired letters, symbols or designs on said surface and formed of tough vulcanized rubber and an admixture of substantially an equal amount by weight of glue whereby the sheet is rendered substantially inelastic, and an adhesive coating on the back face of the sheet for holding the sheet in adhesively connected relation with said surface.

2. As a new article of manufacture, a sand blasting stencil designed for use in cutting letters, symbols or designs on a surface by way of sand blasting and comprising a sand resistant sheet adapted to be placed against the surface and to have the desired letters, symbols or designs cut out of it, formed of vulcanized rubber and an admixture of substantially an equal amount by weight of glue whereby the sheet is rendered substantially inelastic and having a fine layer of talc on the front face thereof, a coating of permanently tacky pressure sensitive adhesive applied to and covering the back face of the sheet and adapted to hold the sheet in place with respect to said surface, and a protective sheet of holland covering the adhesive coating and adapted to be removed from the latter immediately before placement of the sand resistant sheet against said surface.

3. As a new article of manufacture, a stencil designed for use in cutting letters, symbols or designs on a surface by way of sand blasting and comprising a sand resistant sheet adapted to be placed against the surface and upon proper shaping thereof to control the sand blast so that it forms the desired letters, symbols or designs on said surface, and formed of tough vulcanized rubber and an admixture of substantially an equal amount by weight of glue whereby the sheet is rendered substantially inelastic, and a coating of permanently tacky, pressure sensitive adhesive applied to and covering the back of the sheet and adapted to hold the sheet in adhesively connected relation with said surface.

4. As a new article of manufacture, a stencil designed for use in cutting letters, symbols or designs on a surface by way of sand blasting and comprising a sand resistant sheet adapted to be placed against the surface and upon proper shaping thereof to control the sand blast so that it forms the desired letters, symbols or designs on said surface, and formed of tough vulcanized rubber, an admixture of substantially an equal amount by weight of glue whereby the sheet is rendered substantially inelastic, and a filler in greater amount than either the rubber or the glue, and an adhesive coating applied to and covering the back face of the sheet and adapted to hold the sheet in adhesively connected relation with said surface.

5. As a new article of manufacture, a stencil designed for use in cutting letters, symbols or designs on a surface by way of sand blasting and

comprising a sand resistant sheet adapted to be placed against the surface and upon proper shaping thereof to control the sand blast so that it forms the desired letters, symbols or designs on said surface, and formed of tough vulcanized rubber, an admixture of substantially an equal amount of glue whereby the sheet is rendered substantially inelastic, and whiting in an amount by weight substantially equal to the combined amount of the rubber and glue, and a coating of permanently tacky pressure sensitive adhesive applied to and covering the back face of the sheet and adapted to hold the sheet in adhesively connected relation with the surface.

6. As a new article of manufacture, a sand blast stencil designed for use in cutting letters, symbols or designs on a surface by way of sand blasting and comprising a sand resistant sheet adapted to be placed against the surface and upon proper shaping thereof to control the sand blast so that it forms the desired letters, symbols or designs cut on said surface, and formed by spreading into layer form, and then vulcanizing, a plastic mass including approximately 25% milled rubber, approximately 50% filler, approximately 25% glue, and extremely small quantities of a vulcanizing agent and an accelerator for the agent; and an adhesive coating applied to and covering the back of the sheet and serving to hold the sheet in adhesively connected relation with the surface.

7. As a new article of manufacture, a sand blast stencil designed for use in cutting letters, symbols or designs on a surface by way of sand blasting and comprising a sand resistant sheet adapted to be placed against the surface and to have the desired letters, symbols or designs cut out of it, and formed by spreading into layer form, and then vulcanizing, a plastic mass including approximately 25% milled rubber, approximately 50% filler material, a small quantity of zinc oxide, approximately 25% glue, and extremely small quantities of petrolatum, tetramethylthiuram disulphide and sulfur; and a coating of permanently tacky pressure sensitive adhesive applied to and covering the back face of the sheet and adapted to hold the sheet in adhesively connected relation with the surface.

8. A stencil adapted for use in cutting letters, symbols or designs on a surface by way of sand blasting and comprising a sand resistant sheet adapted to be placed against the surface and upon proper shaping thereof to control the sand blast so that it forms or cuts the desired letters, symbols or designs on said surface, provided on the back face thereof with a coextensive coating of permanently tacky pressure sensitive adhesive for holding it in adhesively connected relation with said surface, and formed by spreading into layer form, and then vulcanizing, a plastic mass including the following ingredients in substantially the proportions specified:

	Pounds	Ounces	
Milled rubber.....	50	0	65
Whiting.....	98	0	
Zinc oxide.....	2	0	
Glue.....	50	0	
Petrolatum.....	0	4	
Tetramethyl-thiuram disulphide.....	0	6	
Sulfur.....	0	10	70
